CLAIM

The ornamental design for a key safe, as shown and described.

DESCRIPTION

FIG. 1 is a bottom, front and left side perspective view of a key safe showing my new design;
 FIG. 2 is a front elevational view thereof;
 FIG. 3 is a rear elevational view thereof;
 FIG. 4 is a left side elevational view thereof;
 FIG. 5 is a right side elevational view thereof;
 FIG. 6 is a top plan view thereof; and,
 FIG. 7 is a bottom plan view thereof.

The broken lines in the drawings illustrate portions of the key safe which form no part of the claimed design.
 The oblique shade lines in the drawings represent reflective surfaces.
